DENTIFRICE COMPOSITIONS CONTAINING SURFACE-ACTIVE N-(2-HYDROXYALKYL)-N-METHYLTAURINE-N-OXIDE

Arno Cahn, Pearl River, and Thaddeus J. Kaniecki, New York, N.Y., assignors to Lever Brothers Company, New York, N.Y., a corporation of Maine

No Drawing. Filed Feb. 15, 1962, Ser. No. 173,377
8 Claims. (Cl. 167—93)

This invention relates to N-(2-hydroxyalkyl)-N-methyltaurine-N-oxides, alkali metal salts thereof, and methods of preparation. The invention additionally relates to detergent and dentifrice compositions containing N-(2-hydroxyalkyl)-N-methyltaurine-N-oxides and alkali metal salts thereof as active ingredients.

The compounds,

where R is an alkyl group having from 8 to 18 carbon atoms, and M is selected from the group consisting of hydrogen and alkali metals, have been discovered.

The novel compounds of this invention are excellent surface active agents, and are useful in detergent and dentifrice formulations. The N-(2-hydroxyalkyl)-N-methyltaurine-N-oxides show detergency characteristics, both alone and in the presence of conventional builder salts, such as alkali metal sulfates, carbonates, silicates, phosphates, borates, and mixtures thereof. The presence of conventional detergent builders generally improves the detergency of the compositions. Additional components, such as carboxymethylcellulose, which improves the dirt suspending properties of the washing solution, may be used. Also, other synthetic detergents, soaps, perfumes, abrasives, foam stabilizers, germicidal agents, coloring agents and the like, may be included in the detergent compositions of this invention. Accordingly, they are useful in dish washing detergents, non-soap bars, soap bars, bars containing mixtures of soaps and non-soaps, shampoos, and to other applications known to those skilled in the art where surface active properties are desired.

As will be noted below, another significant advantage of the compounds of this invention is that the compounds within the series having the best detergent characteristics are those where R has a chain length of 13 to 18 carbon atoms, and can thus be obtained from less expensive raw materials.

The N-(2-hydroxyalkyl)-N-methyltaurine-N-oxides of this invention are particularly useful in dentifrice compositions, such as toothpaste. These compounds produce a large amount of foam, and do not lose their foaming power during the normal storage period while the compound is in contact with the other toothpaste ingredients. By comparison, the parent compounds, before conversion to the N-oxide, rapidly lose all ability to form a foam during storage.

The N-(2-hydroxyalkyl)-N-methyltaurine-N-oxides, of this invention are prepared by the oxidation of the corresponding N-(2-hydroxyalkyl)-N-methyltaurine, according to the following equation:

R and M having the same meaning as given above. While hydrogen peroxide is the preferred oxidizing agent, others

2

such as ozone, which have been described in the literature for the conversion of amines to amine oxide may be used.

The N-(2-hydroxyalkyl)-N-methyltaurine may be prepared with ease from starting materials which are relatively inexpensive and commercially available, as described in our co-pending application Serial No. 116,706, filed June 15, 1961. A desirable method of preparing these compounds is by the simple addition of N-methyltaurine to a long chain 1,2-epoxyalkane. This simple addition technique produces the desired N-(2-hydroxyalkyl)-N-methyltaurine, and the reaction product is free from inorganic salts which are difficult to remove. Inorganic salts are highly objectionable, particularly when the compounds are to be used in detergent formulations. The preparation of the epoxide starting material may be by conventional methods such as oxidation of the compounds derived from petroleum sources.

The following examples describe the preparation and characteristics of the compounds of this invention, and also illustrate their usefulness as active ingredients in detergent and dentifrice formulations.

EXAMPLE I

A series of the novel compounds of this invention was prepared according to the following general procedure.

60 ml. of 30% hydrogen peroxide (0.536 mole) was slowly added to a warm alcoholic solution of sodium N-(2-hydroxyalkyl)-N-methyltaurine, prepared by dissolving 0.134 mole of sodium N-(2-hydroxyalkyl)-N-methyltaurine in 350 ml. of 95% ethyl alcohol. The resultant solution was maintained at 40–50° C. for 24 hours. The excess hydrogen peroxide was then decomposed by placing a 1" x 2" pieces of platinum foil into the solution and allowing it to remain there for 2 to 4 days. When gas bubbles no longer formed on the surface of the platinum, it was removed from the reaction solution and the solvent was evaporated off. The last traces of solvent were removed by drying the residue at reduced pressure. The residue was finely powdered and suspended in 200 ml. of acetone. The suspension was warmed to 40° C., filtered and the product air dried. Final drying was for 6 hours in a vacuum oven at 30 mm. and 50° C. Table I lists the compounds prepared with this procedure.

Table I

GENERIC FORMULA

Where R =	Yield (isolated), percent
C ₁₀ H ₂₁ —	97.5
C ₁₂ H ₂₅ —	98
C ₁₄ H ₂₉ —	98
C ₁₆ H ₃₃ —	97.5
C ₉ H ₁₉ —C ₁₃ H ₂₇ (mixture)	81
C ₁₃ H ₂₇ —C ₁₈ H ₃₇ (mixture)	100

EXAMPLE II

A series of N-(2-hydroxyalkyl)-N-methyltaurine-N-oxides was prepared by the method of Example I and tested for detergency by the Terg-O-Tometer Detergency Test. This test gives an empirical measurement of the amount of soil removed from the fabric under simulated washing conditions. Sample swatches of cloth soiled in a standard manner with a standard soil are placed in a miniature washing machine, the Terg-O-Tometer apparatus, and laundered in the presence of a measured amount of detergent and water of a standard hardness. A Terg-O-Tometer apparatus is described in the Journal of the American Oil Chemists' Society, vol. 27, May 1950, pp.

153-159. After rinsing and drying the reflectance of the cloths is measured and compared with the reflectance of the soiled cloths before washing.

In the detergency test referred to herein, the Terg-O-Tometer apparatus was maintained in a water bath adjusted to maintain the temperature of the washing solution at 120° F. ± 2° F. The paddle oscillation was brought to ninety complete cycles per minute and the paddle oscillated through a 320° arc.

With the agitators in position on the machine, the detergent was added in the desired amount to the washpot of the machine. 1250 ml. of water having a hardness of 180 p.p.m. CaCO_3 (60 parts magnesium and 120 parts calcium calculated as calcium carbonate) was added. The machine was started and the solution agitated until the detergent was dissolved.

Cloth swatches approximately 4½ inches by 6 inches were then added and the washing was continued for twenty minutes, after which the test swatches were removed from the solution and hand squeezed. The washpot was refilled with clear rinse water of the same hardness used for washing at a temperature of 120° F. ± 2° F., and, with the agitators running, the cloths were rinsed for 5 minutes. The cloths were then removed, hand squeezed and ironed dry. The reflectance of the cleaned cloths was measured with the Hunter Reflectometer using the green filter.

The Terg-O-Tometer test was carried out in duplicate. The reflectance values in the table below represent the average of the actual reflectance readings taken from eight cloth swatches. Each of the N-(2-hydroxyalkyl)-N-methyltaurine-N-oxides was evaluated alone and in the presence of tetrapotassium pyrophosphate, a conventional builder. Table II summarizes the results obtained.

Table II

TERG-O-TOMETER—HOMOLOGOUS SERIES OF SODIUM N-(2-HYDROXYALKYL)-N-METHYLTAURINE-N-OXIDES OF FORMULA

Compound	CH ₃	Reflectance Readings, Hunter Reflectometer with Green Filter	Level, 0.05% by weight	0.025% by weight of compound plus 0.05% by weight of TKPP ¹
R = $\text{C}_{10}\text{H}_{21}$	41.7	43.4		
R = $\text{C}_{12}\text{H}_{25}$	44.9	47.3		
R = $\text{C}_{14}\text{H}_{29}$	45.5	51.4		
R = $\text{C}_{16}\text{H}_{33}$	45.4	52.1		
TKPP ¹	43.8			
(Sodium) Dodecylbenzenesulfonate	42.9	46.9		
Water	41.2			
Soil Cloth-Initial Average	39.0			

¹ Tetrapotassium pyrophosphate.

EXAMPLE III

Sodium N-(2-hydroxyalkyl)-N-methyltaurine-N-oxides were prepared from sodium - N - (2-hydroxyalkyl)-N-methyltaurines, which were in turn prepared by reacting N-methyltaurine with a 1,2-epoxyalkane mixture in which the alkane portion had, in one case, carbon chain lengths ranging from C_{15} to C_{20} , and in the other case, from C_{11} to C_{15} . The method of preparation described in Example I was employed. These compounds were evaluated by the Terg-O-Tometer Test, both alone and in the presence of tetrapotassium pyrophosphate. The mixed alkyl products showed slight detergency alone and gave a good-to-excellent response to building. Table III below gives the results of these evaluations.

4
Table III

TERG-O-TOMETER TESTS OF SODIUM N-(2-HYDROXY-ALKYL)-N-METHYLTAURINE - N - OXIDES OF FORMULA:

Compound	Reflectance Readings, Hunter Reflectometer with Green Filter	Level, 0.05% by weight	0.025% by weight of compound plus 0.05% by weight of TKPP ¹
R = $\text{C}_{9}\text{H}_{19}-\text{C}_{13}\text{H}_{27}$ mix.	42.9		48.2
R = $\text{C}_{12}\text{H}_{27}-\text{C}_{16}\text{H}_{37}$ mix.	42.6		51.0
(Sodium) Dodecylbenzenesulfonate	42.9		46.9
TKPP ¹	43.8		
Water	41.2		
Soil Cloth-Initial Average	39.0		

¹ Tetrapotassium pyrophosphate.

EXAMPLE IV

Three compounds of this invention were evaluated according to the RAP Mildness Evaluation Test for Detergents. In this test, a 2% aqueous solution of the compound was tested on rabbit skin and the results rated according to the following scale.

Mildness rating:

- 0—No epidermal erosion (very mild)
- 1—Foci or small patches of erosion (fair mildness)
- 2—25% to 50% destruction of epidermis (irritating)
- 3—Greater than 50% epidermal erosion (very irritating)

Table IV below gives the compounds tested and the results of the test.

Table IV

Compound	Mildness Rating	Remarks
Sodium N-(2-hydroxydodecyl)-N-Methyltaurine-N-Oxide.	0	Epidermis normal.
Sodium N-(2-hydroxytetradecyl)-N-Methyltaurine-N-Oxide.	0	Do.
Sodium N-(2-hydroxyoctadecyl)-N-Methyltaurine-N-Oxide.	0	Do.

EXAMPLE V

A principal utility of N-(2-hydroxyalkyl)-N-methyltaurine-N-oxides is their application as dentifrice detergents. The following test procedure was used to measure the foaming ability of a toothpaste formulation:

A 2 gram sample of an experimental toothpaste formulation containing the detergent compound under investigation was introduced into a 50 ml. beaker containing 5 ml. of distilled water. The toothpaste formulation was as follows.

Ingredient:	Percent by weight
Dicalcium phosphate dihydrate	50.00
Other powdered abrasives	5.50
Gum binder	.50
Humectant, flavor, and misc. ingredients	36.15
Glycerine	5.85
N - (2-hydroxytetradecyl)-N-methyltaurine-N-oxide ¹	2.00
	100.00

¹ Where sodium lauryl sulfate was used, it was added at a level of 1.16%, and the glycerine level adjusted to 6.69%.

The toothpaste was thoroughly dispersed by gentle stirring, and the dispersion then transferred to a 100 ml. graduated cylinder. The beaker was washed with 15

ml. of distilled water and the washings also transferred to the cylinder. The cylinder was then inverted 25 times and allowed to rest for 5 minutes before reading the foam volume.

A toothpaste containing 2% of N-(2-hydroxytetradecyl)-N-methyltaurine-N-oxide produced a 70 ml. foam volume in this test as compared with a foam volume of 40 ml. obtained with a toothpaste containing a conventional detergent, sodium lauryl sulfate, at a level of 1.16%. No change in the foaming power of the N-oxide toothpaste was noted over a one month aging period, while a similar toothpaste containing N-(2-hydroxytetradecyl)-N-methyltaurine as the detergent, failed to exhibit any foam whatsoever after the same period of storage.

EXAMPLE VI

Another important property of toothpaste is freedom from irritation of mucous membranes. A mucous membrane study was made comparing the irritation potential of a toothpaste containing N-(2-hydroxytetradecyl)-N-methyltaurine-N-oxide at a 2% concentration level and a similar toothpaste containing 1.14% of sodium lauryl sulfate.

A small amount of each toothpaste was applied to the vaginal tissue of each of six young adult female rabbits. These were divided into two groups, one for each formulation, placing three animals in each group. The paste was applied for three consecutive days and observations made over seven days for signs of irritation to the mucous membrane. No inflammatory reaction was noticed in either group of rabbits. The experimental paste was determined to be without primary irritation.

EXAMPLE VII

The acute oral toxicity of N-(2-hydroxytetradecyl)-N-methyltaurine-N-oxide was determined in the following manner:

A slurry containing the tetradecyl compound was force fed into the stomachs of ten mice using a hypodermic syringe and a stomach tube. The slurry contained 1 gram of the compound and 9 cc. of water, and was injected at a dosage of 2 grams of slurry per kilogram of body weight. The average weight of the mice was 25 grams. No deaths were observed after a period of 14 days.

We claim:

1. A dentifrice composition comprising an abrasive and a compound of the formula

wherein R is an alkyl group having from 8 to 18 carbon atoms and M is selected from the group consisting of hydrogen and the alkali metals.

2. The dentifrice composition of claim 1, wherein the compound is N-(2-hydroxydodecyl)-N-methyltaurine-N-oxide.

3. The dentifrice composition of claim 1, wherein the compound is N-(2-hydroxytetradecyl)-N-methyltaurine-N-oxide.

4. The dentifrice composition of claim 1, wherein the compound is the sodium salt of N-(2-hydroxydodecyl)-N-methyltaurine-N-oxide.

5. The dentifrice composition of claim 1, wherein the compound is the sodium salt of N-(2-hydroxytetradecyl)-N-methyltaurine-N-oxide.

6. The dentifrice composition of claim 1, wherein the compound is one where R is a mixture of C₉ to C₁₆ alkyl groups.

7. The dentifrice composition of claim 1, wherein the compound is the sodium salt of N-(2-hydroxyhexadecyl)-N-methyltaurine-N-oxide.

8. In a method of cleaning teeth, the step of applying to the surface of the teeth, a compound of the formula

wherein R is an alkyl group having from 8 to 18 carbon atoms and M is a member of the group consisting of hydrogen and the alkali metals.
